UNITED STATES PATENT OFFICE.

WILLIAM F. ANKLAM, OF DETROIT, MICHIGAN, ASSIGNEE TO C. M. HALL LAMP COMPANY, OF DETROIT, MICHIGAN, A CORPORATION OF MICHIGAN.

LAMP.

1,131,652.

Specification of Letters Patent. Patented Mar. 16, 1915.

Application filed October 21, 1913. Serial No. 796,381.

To all whom it may concern:

Be it known that I, WILLIAM F. ANKLAM, a citizen of the United States of America, residing at Detroit, in the county of Wayne and State of Michigan, have invented certain new and useful Improvements in Lamps, of which the following is a specification, reference being had therein to the accompanying drawings.

10 The invention relates to lamps particularly designed for use on motor vehicles, and it is the object to obtain a construction in which two lamps of different power are arranged within a common case without interference with each other. Thus a single lamp fulfills the purpose of the headlight and dash-lights.

It is usual in headlight construction to focus the rays by a parabolic reflector, which 20 limits the angle of distribution and concentrates the light. It is necessary, however, that the filament of the lamp should be located at the proper point for focusing, and it is equally important that there should be 25 no obstruction between the lamp and the reflector. Thus, where two different lamps are placed in the same case both cannot be in focus, while the one out of focus will obstruct the rays from the one in focus. With 30 my improved construction I have overcome this defect by placing the main, or high power lamp, in proper position of focus in relation to the parabolic reflector, while the auxiliary lamp is placed in a niche in the 35 reflector wall, the walls of the niche being formed to produce a second reflector for the auxiliary lamp.

As shown in the drawings: Figure 1 is a vertical, central, longitudinal section 40 through the lamp reflector, the outer casing being omitted; Fig. 2 is a front elevation thereof; and Fig. 3 is a section on line α — α Fig. 1.

A is the reflector for the main lamp, which 45 is of usual parabolic form.

B is an electric lamp placed in position for focus in relation to this reflector and supported in a cylindrical lamp socket C projecting from the rear of the reflector.

50 D is a niche formed in the upper wall of the reflector A and having walls of the proper contour to form an auxiliary reflector E. At the rear of the niche is a lamp socket F for receiving the auxiliary lamp G.

and holding the latter in proper relation to the reflector. A slight longitudinal adjustment of the lamp in its socket will effect accurate focusing and a similar method of adjustment is provided for the main lamp B. To hold the lamp G in proper position 60 of adjustment the projecting tubular socket F is preferably split at H and provided with a tapering external thread engaged by a ring-nut I. Thus when the nut is screwed on to the socket it will contract its diameter 65 and clamp the lamp therein.

The construction described is one which is adapted to be used with any suitable construction of lamp case, the bulge in the reflector formed by the niche D being arranged in the usual space provided between the reflector and the outer case, while this space also provides for the electrical connections to the lamps. These connections are formed of flexible conductors as indicated at 75 J and K and are attached to a common plug socket L for engagement with the aperture in the outer case, not shown. Thus both lights may be controlled through a common multiple connector, and as both the lamps 80 and their connections are mounted upon the main reflector, the engagement with the case is facilitated.

What I claim as my invention is:

1. The combination with a main reflector 85 and a lamp focusable in relation thereto, of an auxiliary lamp arranged in a niche in said reflector.

2. A parabolic lamp reflector having a 90 niche or depression in a portion of its wall forming an auxiliary reflector, an auxiliary lamp in said niche, and a main lamp focusable in relation to said parabolic reflector.

3. A detachable lamp reflector, main, and auxiliary, electric lamp bulbs mounted on 95 said reflector, electrical connections to said lamps, and a common socket attached to said connections and removable with the reflector.

4. A detachable lamp reflector of general 100 parabolic form and provided with a niche or depression at one point in its wall, main and auxiliary lamps located respectively in focusable relation to the main reflector and in the niche therein, tubular lamp sockets 105 for said lamps projecting rearwardly from said main reflector and niche, and a connector carried by and detachable with said re-

flector, including a common plug socket and branch connections therefrom to the respective lamps.

5. A lamp reflector, having its walls fashioned for the focusing of a main lamp, and having in one portion a niche or depression forming a reflector for an auxiliary lamp.

6. A parabolic lamp reflector, having a niche in a portion of its wall forming an auxiliary lamp reflector.

7. A parabolic lamp reflector, having a

niche in a portion of its wall forming an auxiliary lamp reflector, and tubular sockets, projecting respectively rearward from the main and auxiliary reflectors.

15

In testimony whereof I affix my signature in presence of two witnesses.

WILLIAM F. ANKLAM.
